(57) **CLAIM**

The ornamental design for a charging station, as shown and described.

DESCRIPTION

FIG. 1 is a perspective top view of the charging station.

FIG. 2 is a front view thereof;

FIG. 3 is a back view thereof;

FIG. 4 is a right side view thereof;

FIG. 5 is a left side view thereof; and,

FIG. 6 is a top view thereof.

The bottom view, which is not illustrated, has no ornamental features and does not form part of the claimed design.

The broken lines in the drawings represent portions of the charging station that form no part of the claimed design.
